(57) **CLAIM**

The ornamental design for a receptacle for pit-containing products, as shown and described.

DESCRIPTION

FIG. 1 is a perspective view of receptacle embodying the claimed design;

FIG. 2 is a view of the portions of the receptacle in FIG. 1 in separated position;

FIG. 3 is a top view of the receptacle in FIG. 1;

FIG. 4 is a bottom view of the receptacle in FIG. 1;

FIG. 5 is a view of one side of the receptacle in FIG. 1; and,

FIG. 6 is a view of the other side of the receptacle in FIG. 1.

The broken lines represent environment and portions of the structure that form no part of the claim.
